(57) CLAIM

The ornamental design for a tablet PC protection cover, as shown and described.

DESCRIPTION

FIG. 1 is a perspective view of a tablet PC protection cover; FIG. 2 is a front elevational view of thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is another perspective view thereof; FIG. 9 is a perspective thereof shown with the strap in an alternate configuration of use; and, FIG. 10 is an enlarged view showing one part of FIG. 8. In the drawings, the broken lines illustrate portions of the article that form no part of the claimed design.
